UNITED STATES PATENT OFFICE.

MILTON ALDEN, OF SPRINGFIELD, MASSACHUSETTS, ASSIGNOR TO DENTAL ELECTRIC COMPANY, OF SPRINGFIELD, MASSACHUSETTS, A CORPORATION OF MASSACHUSETTS.

ELECTRICAL SUPPLY APPARATUS.

1,330,153.

Specification of Letters Patent. Patented Feb. 10, 1920.

Application filed November 12, 1917. Serial No. 201,719.

To all whom it may concern:

Be it known that I, MILTON ALDEN, a citizen of the United States of America, residing at Springfield, in the county of Hampden and State of Massachusetts, have invented certain new and useful Improvements in Electrical Supply Apparatus, of which the following is a specification.

This invention relates to improvements in electrical supply apparatus, such, for example, as are used by dentists, surgeons, and others for supplying electrical energy to instruments of various kinds.

Electrical instruments have found favor in modern dentistry and surgery and are rapidly coming into extensive use. These instruments, due to the character of the work for which they are designed, cannot readily be operated at high voltages and are purposely constructed for operation at relatively low voltages to avoid injury to the patient. Generally, however, the only convenient source of electrical energy is the commercial alternating current lighting circuit, the voltage of which is seldom low enough for the purposes desired. Accordingly step down transformers are employed to reduce the voltage within the required limits. It is also desirable in dental and surgical instruments to be able to vary the voltage as some instruments require higher voltages than others and other instruments, such as cauterizing tools, are operated at varying voltages depending upon the character of the work to be performed. This necessitates the use of a rheostat or equivalent controlling device. This invention is concerned among other things with the provision of a portable compact apparatus which embodies the essential transformer and rheostat within a single casing and which is arranged for convenient use with electrical instruments without requiring attention on the part of the operator.

An object of the invention is to provide in an instrument of the character described holding means in which electrical instruments may be supported for convenient removal and switches in the electrical circuit of each instrument arranged to automatically close and energize the instruments when the latter are removed from their holding means and to automatically open and de-energize the instruments as soon as the latter are replaced.

A further object of the invention is to provide generally simplified and improved mechanical means for automatically operating instrument controlling switches of the type described.

Other objects and advantages will appear in the following description and will be particularly pointed out in the appended claims.

The invention, in an embodiment at present preferred, is shown for illustrative purposes in the accompanying drawings, in which—

Figure 1 is a side elevational view of the apparatus;

Fig. 2 is an enlarged plan view thereof;

Fig. 3 is an enlarged bottom plan view of the cover shown as removed from the apparatus;

Fig. 4 is an enlarged top plan view of the apparatus with the cover removed;

Fig. 5 is an enlarged cross sectional view taken on the line 5—5 of Fig. 2;

Fig. 6 is a bottom plan view of the arm for supporting instruments used with the apparatus and shows the switch inclosing casing;

Fig. 7 is a perspective view of the switch inclosing casing shown as removed from the arm; and

Fig. 8 is a diagrammatical view of the electrical connections of the apparatus.

Referring to these drawings, the apparatus involves a casing 10, which may be suitably supported in any desired manner as, for example, by a pedestal 11 through the intermediary of a swivel joint indicated conventionally at 12. Within the casing 10 is a suitable transformer 13 (Fig. 4) which is adapted, as will appear, for connection to a suitable source of electrical energy, the supply wires 14 for the transformer passing through a wall of casing 10 and preferably through the pedestal 11, as indicated in Fig. 1. The upper end of casing 10 is in closed by a cover 15 of insulating material and on the bottom face of the cover is a suitable rheostat, such as a helical coil 16 of resistance wire bent into circular form and secured to the cover. The rheostat has an arm 17 adapted to play over the lower ends of coil 16 which arm is mounted in cover 15 and is rotatable by a knob 18 on the top of the cover. A pointer 19 movable with arm 17 plays over a dial 20, which

may be graduated in suitable units as volts, for example. Also mounted on the cover 15 are two pairs of binding posts 21 to which the flexible cords 22 of suitable electrical instruments 23 are removably attached. The instruments may be of any suitable type and the left and right hand instruments, which are shown herein merely for illustrative purposes, represent a combined lamp and mirror and a cauterizing tool, respectively.

The electrical apparatus described is connected as indicated in Fig. 8, the connections having been omitted in the other figures to avoid confusion with mechanical structure. The primary and secondary coils of transformer 13 are indicated at 24 and 25 and one end of the former is connected to a source of alternating current. The other end of coil 24 is connected by a wire 26 to two upper fingers 27, which engage fingers 28 as indicated, the lower fingers 28 being electrically connected together and to the source of current by a wire 29. Thus, when either finger 27 engages its finger 28 the transformer 13 is energized.

One terminal of secondary coil 25 is connected by a wire 30 to two upper fingers 31 which are adapted to engage with lower fingers 32. The right hand finger 32 is electrically connected by a wire 33 with one of the binding posts 21 of the right hand pair and the left hand finger 32 is similarly connected to one binding post 21 of the left hand pair. The other terminal of coil 25 is connected by a wire 34 to the rotatable contact arm 17 of the rheostat and the coil 16 of the latter is connected by a wire 35 to the other binding post 21 of each pair. If one of the instruments 23 requires a somewhat lower voltage than the other a constant resistance 36 may be interposed in the circuit to its binding posts 21, as indicated. When either finger 31 engages its finger 32, the instrument 23 connected in the circuit therewith is energized.

The fingers 27, 28, 31, and 32 are arranged in right and left hand sets, each set being supported from a common insulating block 37, which, as indicated in Fig. 4, closely fits between an end of transformer 13 and one end wall of casing 10, and as shown in Fig. 5 is held laterally in position by engagement with the side walls of the casing. The several fingers are suitably insulated one from another, as indicated in Fig. 5, and each set of fingers protrudes laterally through openings 38 in the side walls of casing 10. Secured to the latter above each set of fingers is an arm 39 which projects laterally of the casing and beyond the fingers. Fixed to the outer end of each arm 39 is a spring clip 39' which is adapted to support an instrument 23 for convenient removal.

Slidable in the shank of each clip 39' is a pin 40 which has a rounded lower end resting upon an insulating strip 41 secured to and extending from the end of a finger 32. Each finger 28 and 32 extends beyond the fingers 27 and 31, respectively, thereabove and these extended ends are separated by an insulating block 42. The fingers 28 and 32 are so constructed as to spring upwardly into engagement with their fingers 27 and 31, respectively, and thus an instrument 23, when removed from its clip 39', immediately becomes energized, and, when replaced, it is automatically deenergized. The spring action of the upper fingers 32 is utilized also as a means to force pins 40 upwardly in clips 39' when an instrument is removed.

In order to inclose the fingers projecting through openings 38 and to close the latter, housings 43 are provided. The latter may be advantageously formed from a single piece of metal pressed into the form best shown in Fig. 7. As there shown, the housing is open at the top and at one end. Along each upper edge of the housing an outwardly turned flange 44 is provided and formed in each flange adjacent the open end of the housing is a notch 45. The described arm 39 has in its lower face two pairs of headed pins 46 fixed to the arm in spaced relation therealong. The heads of pins 46 are spaced below arm 39 just sufficiently to receive therebetween the flanges 44 (Fig. 5). The pins 46 of each pair are spaced laterally just sufficiently so that the housing may be slid along the arm with the outer edge of each flange bearing against the inner edge of a pin. The top opening of the housing 43 is then closed by the arm 39 and the open end of the housing abuts casing 10 to close opening 38. The distance between flanges 44 is made slightly greater adjacent the open end than adjacent the closed end of the housing. The sides of the housing adjacent its open end are then pressed together slightly as the housing is slid into position on arm 39 so that the flanges will fit between a pair of pins 46. The metal of which the housing is constructed has sufficient spring action so that, when notches 45 align with the inner pair of pins 46, the side walls of the casing spring outwardly forcing the notched portions into engagement with the pins. It will thus be seen that the housing may be removably held in position on the arm and that it may be readily removed and replaced to permit convenient inspection and repair of the contact fingers.

An important feature of the invention consists in the arrangement, whereby each instrument is automatically energized when it is removed from its holder and automatically deenergized when replaced therein. It is to be noted particularly that not

only are the secondary circuits to the instruments opened when an instrument is placed within the holder, but when both instruments are replaced the supply circuit 5 to the primary coil of the transformer is also opened. The particular mechanism for accomplishing this result is also of importance in an instrument of this type. The mechanism is simple in construction and advantageously arranged for positive and efficient action without a multiplicity or complication of parts.

Thus an electrical supply apparatus of generally simplified and improved construction has been provided. It is recognized that modifications may be made in the structure herein described for illustrative purposes without departing from the scope of the invention which is defined by the appended claims rather than by the foregoing description.

What I claim is—

1. An apparatus of the class described, comprising, a casing, a plurality of holding means thereon to removably support electrical instruments, sets of terminals on the casing to which said instruments may be electrically connected, a transformer the primary coil of which is adapted for connection at one end to a source of electrical energy, an electrical circuit from the secondary coil of the transformer to each set of terminals, a switch in each circuit arranged to close automatically, and means 30 associated with each holding means to open

its switch when an instrument is positioned in its holding means, whereby the instrument is automatically deenergized, another switch associated with each of the first-named switches and constructed to open and close therewith, and electrical connection 40 between one terminal of each of the last-named switches to the other end of said primary coil, the other terminal of each of the last-named switches being adapted for 45 electrical connection to said source, whereby when an instrument is positioned in each holding means the circuit to said primary coil is interrupted.

2. In an apparatus of the class described, 50 a casing, an arm projecting therefrom, means on the arm to removably support an electrical instrument, a switch comprising normally engaged spring contact fingers supported at one end in the casing and protruding at the other end through the casing and below said arm, a slideable pin in the clip, an extension on one of said fingers adapted to support an end of said pin, the other end of the latter adapted to be engaged as an instrument is inserted in the clip and depressed to open said switch, and a housing removably secured to said arm and inclosing said fingers, the housing being 55 constructed and arranged for removal from without the casing, whereby the contact fingers may be conveniently inspected, adjusted, and repaired.

MILTON ALDEN.
